ELECTRON TUBE

Clarence W. Hansell, Rocky Point, N. Y., assignor
to Radio Corporation of America, a corporation
of Delaware

Application September 13, 1934, Serial No. 743,813

15 Claims. (Cl. 250—27.5)

This invention relates primarily to electron tubes and is more particularly directed to tubes of the cathode ray type wherein an electron stream is produced and directed from an electron source toward an anode electrode and shifted in its passage between the source and the electrode by means of some suitable deflecting field.

One of the primary objects of the present invention is that of eliminating the effects of secondary emission from the anodes upon which the electron stream impinges.

A further object of the invention is that of lowering the internal resistance of the tube to the flow of electron currents.

Still a further object of the invention relates to general improvements in the design of electron tube structure.

By the prior art, as is evidenced, for example, by my previously issued Patent No. 1,850,104, granted on March 22, 1932, assigned to Radio Corporation of America, I have shown an electron tube particularly adapted for a system wherein the effects of tube noises are eliminated and have applied a tube of the cathode ray type to use in an amplifying system. By this arrangement of the prior art the effects of secondary emission from the anodes were reduced to some extent by providing a shield between the two anodes and the source of electrons. However, by the present invention I have been able to overcome to a still greater extent the detrimental effects of secondary emission in tube operation in a manner which was not heretofore attainable.

Briefly, the new feature embodied in the present invention consists in the use of cup-like anodes so designed and spaced relative to the elements of the accelerating grid that all of the electrons issuing from the emitting element striking the anodes do so inside the cup-shaped portion where there is very little, if any, potential gradient and where, as a result, secondary emission which results from electron impact will not be drawn out.

The invention is illustrated in one of its suggested forms by the accompanying drawing, wherein:

Fig. 1 represents conventionally a sectional view through an electron tube of the type herein disclosed and shows the tube applied to an operating circuit of the general type shown in my previously acknowledged patent; and

Fig. 2 illustrates a tube of the type shown in Fig. 1 also in section along the line 2—2 of Fig. 1 looking in the direction of the arrows.

If reference is now made to the accompany-

ing drawing, it will be seen that I have provided a tube 1 formed of a glass envelope and appropriately evacuated. Within the tube 1 and supported from the stem portion 3, I have provided a large area cathode 5 which preferably 5 consists of a thin piece of metal heated by low voltage low frequency electric current supplied thereto by means of conductors 7 and 9 at one end and 7' and 9' at opposite end, so that two parallel supply paths are formed. The cathode 10 of the preferred type as I have shown it preferably has a cross-section in a plane at right angles to its length which approximate very closely a parabola, since I have found that a large area cathode of parabolic shape will result in large 15 electron emission combined with a concentration of the electron stream so that under proper conditions a closely concentrated beam of electrons of considerable strength will be focused upon the center of the accelerating grid structure 11. 20

The focusing of the electron stream issuing from the cathode may further be improved by means of suitable control electrodes 13, for example, which are arranged substantially adjacent the emitting cathode and are given such shaping 25 as to make them substantially continuations of the parabolic shaping of the cathode. Of course, it is desirable in most cases to provide some spacing between the controlling electrodes 13 and the cathode structure 5 for insulating purposes. 30 The electron beam thus issuing from the cathode surface 5 and passing through the grid 11 and controlled by the controlling electrodes 13 is arranged to impinge upon the internal portion of the cup-like anode members 15, 16 which are 35 supported within the end of the tube opposite the electron source.

As I have already pointed out in what has gone before, electrons issuing from the emitting surface 5 are drawn over to the anode members 15 40 and 16 by virtue of the voltage applied between the anode and the emitter and upon striking the anode tend to cause the anode surface to emit secondary electrons. By arranging the anode electrodes in cup-shaped fashion, as above explained, the effects of secondary emission do not extend beyond the boundary confines of the anode structure and, therefore, will not result in a current flowing from the anodes.

In order to provide further improvements in 50 the operation of a tube of the general type herein disclosed, I have arranged at each end of the emitting electrode 5 a shield member 17, 19 for the purpose of concentrating the electron stream in a direction parallel to the length of the cath- 55

ode so that instead of spreading out within the tube and perhaps passing around the accelerating grid structure 11, the electrons are all confined to an area inside the grid where they can 5 pass through the grid and strike the anodes 15 and 16 only inside the cup portion. These shield members 17 and 18 at the ends of the cathode or emitter 5 may be connected either to the cathode structure or to the controlling electrode 10 structure. According to the drawing, the shields are shown as connected to the ends of the cathode and forming, at the same time, a part of the cathode support.

In the construction of a tube of the general 15 type herein shown, the parabolic-shaped thin metal emitting electrode 5 is preferably coated or thoriated in any desired manner so as to have a rather large electron emission.

To prevent emission from one anode 15 or 16 20 reaching the other anode and to guard against any possibility of inefficiencies in operation, shielding structure 21 is supported within the tube to separate the two anodes, and in order to catch most of the electrons when no energy 25 is applied on the control elements and also to catch all electrons which are insufficiently deflected by the deflecting or controlling electrodes 13 to fall within the anode cups, the metal-like bridge structure 23 is provided in the grid. Also, 30 the grid structure in its position between the anodes 15, 16 and the controlling electrode 13 serves to prevent the feedback of push-pull energy of either of the anodes to the controlling electrodes 13.

35 In order to show the general type of system in which a device of this type operates, Fig. 1 of the drawing illustrates one suitable form wherein energy is to be transmitted from one input circuit A to an output circuit B. As was 40 shown in my above mentioned Patent No. 1,850,104, energy supplied from the input circuit A is passed through the transformer coupling 25 tuned by means of the condenser 27 so as to be applied to the controlling electrodes 13 connected to suitable terminals on the base member 28 of the tube 1. The central portion of the 45 secondary of the transformer 25 is connected to ground by way of a suitable conductor 31 in which is included a biasing source 33 for applying suitable negative, positive or even zero potentials to the deflecting or controlling electrodes 13 of the tube in order that the electrodes be biased in suitable manner for operation.

The anode members 15 and 16 connect with 50 the terminals of the primary winding of a secondary output transformer 35 whose secondary feeds energy to a load circuit of any desired type such as a wire line, operating equipment or a radio transmitter, for example, and the output 55 is suitably tuned by means of a condenser 37. Suitable voltage for drawing the electrons from the emitting surface 5 toward the anodes 15, 16 is provided by the inclusion of sources of potential 39 and 41. Between the emitter and the 60 anodes and grids a voltage of the source 41 alone is applied to the grid structure 11. Heating current for heating the emitter 5 is supplied by way of a source 43 and may be either direct or alternating current.

70 Now, if signals are applied in the input circuit A, they are caused to affect or control the controlling or deflecting electrodes 13 and thus cause the electron stream developed to be passed between the two independent cup-like anode members 15 and 16 with the result that current flows

in the output circuit B, as was explained in my previously mentioned patent.

While it has not herein been shown, it is, of course, obvious that certain modifications may be made to the tube structure and the system in 5 which it operates of which only one conventional form has been illustrated, and such a change, for example, may include the design of grid structures which themselves reduce secondary emission. This result may be accomplished 10 through the choice and treatment of the materials used to form the grid structure such, for example, as etching or sand blasting the grid structure so that its surface corresponds to a great number of miniature cups which correspond 15 closely to the cup-shaped anodes.

Other features of modification, of course, will suggest themselves to those skilled in the art to which the invention is directed.

Having thus described the invention, what I claim and desire to secure by Letters Patent is the following:

1. An electron tube comprising an evacuated envelope, an electron emitting element within the envelope, a plurality of cup-shaped anode 25 members symmetrically arranged relative to the emitting element and a pair of deflecting elements intermediate the emitting element and the anodes.

2. An electron tube comprising an evacuated 30 envelope, an elongated electron emitting element of parabolic cross-section, a plurality of cup-shaped anode members symmetrically arranged relative to the emitting element and a pair of deflecting elements intermediate the emitting ele- 35 ment and the anodes.

3. An electron tube comprising an evacuated envelope, an electron emitting element within the envelope, a plurality of cup-shaped anode members symmetrically arranged relative to the electron emitting element, a pair of deflecting elements intermediate the emitting element and the anodes for causing the electron stream to be shifted between the plurality of anodes, and means for shielding the anodes from the deflecting 45 elements.

4. An electron tube comprising an evacuated envelope, an elongated electron emitting element of parabolic cross-section, a plurality of cup-shaped anode members symmetrically arranged 50 relative to the emitting element, and a plurality of deflecting elements positioned intermediate the emitting element and the anodes, said deflecting electrodes lying substantially in the plane ex- 55 tended of the surface of said emitting member.

5. An electron tube comprising an evacuated envelope, an elongated electron emitting element of parabolic cross-section, a plurality of cup-shaped anode members symmetrically arranged relative to the emitting element, a pair of deflecting elements intermediate the emitting element and the anode, and a shield element at each 60 end of the emitting element for preventing spreading of the emitted electrons in a direction longitudinally of the emitting element.

6. An electron tube comprising an evacuated container housing therein an electrode element adapted when heated to emit electrons, a plurality of anode members adapted to receive the electrons issuing from the first electrode, said 70 anode elements being cup-shaped to reduce substantially to zero the effects of secondary electronic emission, a plurality of control electrodes positioned intermediate the electron source and the anode members, and a grid structure inter- 75

mediate the control electrodes and the anodes to provide feed back of energy from the anodes to the control electrodes.

7. An electron tube comprising an evacuated envelope, an elongated electron emitting element of parabolic cross-section for emitting a stream of electrons of substantial dimensions relative to the tube envelope size, a plurality of cup-shaped anode members symmetrically arranged relative to the electron emitting element, a pair of deflecting elements intermediate the emitting element and the anode electrodes for causing the electron stream to be shifted between said plurality of anode electrodes, a shield element at each end of the emitting element for preventing spreading of the emitted electrons in a direction longitudinally of the emitting element, and means within the envelope for shielding the anode electrodes from the deflecting elements and electron source.

8. An electron tube comprising an evacuated container housing therein an electrode element adapted to emit electrons, and an anode electrode adapted to receive the electrons issuing from the emitting electrode, said anode element being constructed cup-shape so that electrons received thereby are unable to cause secondary electronic emission from the anode to have any substantial effect beyond the boundary limits of the anode structure.

9. An electron tube comprising an evacuated envelope, an electron emitting element within the envelope, a plurality of cup-shaped anode members symmetrically arranged relative to the emitting element, means for electrostatically shielding the anode members from each other, and a pair of deflecting elements intermediate the emitting element and the anodes.

10. An electron tube comprising an evacuated envelope, an elongated electron emitting element of parabolic cross-section, a plurality of cup-shaped anode members symmetrically arranged relative to the emitting element, means for electrostatically shielding the anode members from each other, and a pair of deflecting elements intermediate the emitting element and the anodes.

11. An electron tube comprising an evacuated envelope, an electron emitting element within the envelope, a plurality of cup-shaped anode members symmetrically arranged relative to the electron emitting element, means for electrostatically shielding the anode members from each other, a pair of deflecting elements intermediate the emitting element and the anodes for causing the electron stream to be shifted between the plurality of anodes, and means for shielding the anodes from the deflecting elements.

12. An electron tube comprising an evacuated envelope, an elongated electron emitting element of parabolic cross-section, a plurality of cup-shaped anode members symmetrically arranged relative to the emitting element, means for electrostatically shielding the anode members from each other, and a plurality of deflecting elements positioned intermediate the emitting element and the anodes, said deflecting electrodes lying substantially in the plane extended 10 of the surface of said emitting member.

13. An electron tube comprising an evacuated envelope, an elongated electron emitting element of parabolic cross-section, a plurality of cup-shaped anode members symmetrically arranged relative to the emitting element, means for electrostatically shielding the anode members from each other, a pair of deflecting elements intermediate the emitting element and the anode, and a shield element at each end of the emitting 20 element for preventing spreading of the emitted electrons in a direction longitudinally of the emitting element.

14. An electron tube comprising an evacuated container housing therein an electrode element adapted when heated to emit electrons, a plurality of anode members adapted to receive the electrons issuing from the first electrode, said anode elements being cup-shaped to reduce substantially to zero the effects of secondary 30 electronic emission, means for electrostatically shielding the anode members from each other, a plurality of control electrodes positioned intermediate the electron source and the anode members, and a grid structure intermediate the control 35 electrodes and the anodes to provide feedback of energy from the anodes to the control electrodes.

15. An electron tube comprising an evacuated envelope, an elongated electron emitting element of parabolic cross-section for emitting a stream of electrons of substantial dimensions relative to the tube envelope size, a plurality of cup-shaped anode members symmetrically arranged relative to the electron emitting element, means for electrostatically shielding the anode members from each other, a pair of deflecting elements intermediate the emitting element and the anode electrodes for causing the electron stream to be shifted between said plurality of anode electrodes, a shield element at each end of the emitting element for preventing spreading of the emitted electrons in a direction longitudinally of the emitting element, and means within the envelope for shielding the anode electrodes from 55 the deflecting elements and electron source.

CLARENCE W. HANSELL.
